UNITED STATES PATENT OFFICE.

ISRAEL L. CLARK, OF RIVERSIDE, RHODE ISLAND.

PAPERING-BOARD.

1,270,006.

Specification of Letters Patent. Patented June 18, 1918.

Application filed November 7, 1916. Serial No. 130,103.

To all whom it may concern:

Be it known that I, ISRAEL L. CLARK, a citizen of the United States, residing at Riverside, in the county of Providence and 5 State of Rhode Island, have invented certain new and useful Improvements in Papering-Boards; and I do hereby declare the following to be a full, clear, and exact description of the invention, such as will enable 10 others skilled in the art to which it appertains to make and use the same.

This invention relates to new and useful improvements in papering boards adapted for use by paper hangers as work tables.

15 The principal object of the invention is to provide a papering board which may be knocked down and folded into a compact bundle for transportation purposes.

Another object of the invention is to provide 20 a device which will eliminate the necessity of the user carrying a board of any great length or width.

Heretofore much difficulty and inconvenience has been encountered by paper 25 hangers in the use of the ordinary type of papering board due to the fact that they have found it necessary to transport a board measuring in the neighborhood of three feet in width and six or eight feet in length 30 from place to place and to their various places of occupation. The object of this invention is to avoid the necessity of carrying such a board and yet providing a device which may be readily collapsed and will be 35 strong and substantial when in use.

With these and other objects in view, the invention consists in the novel combination and arrangement of parts which will be fully set forth in the following specification 40 and accompanying drawings, in which:—

Figure 1 is a perspective view of the board taken from a point below the upper side thereof to show the construction of the supporting frame and legs.

45 Fig. 2 is a bottom plan view of the device.

Fig. 3 is a fragmentary top plan view of the board.

Fig. 4 is a view similar to Fig. 1, showing the near set of legs removed as the first step 50 of collapsing the device.

Fig. 5 is a sectional view through a fragment of the frame illustrating the corner construction and the method of attaching the legs thereto.

55 Fig. 6 is a detail view of the connection

of the brace to the center transverse strip, and

Fig. 7 is a fragmentary detail perspective view of one end of one of the bracing bars.

Referring to the drawing, the frame or 60 the board comprises a pair of longitudinal side rails consisting of the strips 1, 2, 3 and 4. The strips 1 and 3 are placed end to end and the strips 2 and 4 are placed end to end so as to form a pair of parallel side rails to 65 which the canvas cover or other suitable flexible material 5 is secured. It will thus be seen that the side rails form a part of the supporting frame for the canvas cover and coöperate with the end rails and a center 70 strip which will be more fully hereinafter described. The abutting ends of the strips 1 and 3 and the strips 2 and 4 are formed with alining grooves on their inner faces which coöperate with each other in receiving 75 the tongues of the ends of the center strip as will be more fully hereinafter described. The outer ends of the side rails are also formed with the grooves 6, for a purpose which will be hereinafter described. 80 The end bars or rails of the frame are designated by the numerals 7 and 8 and are each formed with a tongue 9 which is adapted to engage in the grooves 6 formed at the ends of the side rails hereinbefore described. 85 The center strip designated by the numeral 10 is provided with similar tongues at its opposite end which extend into the grooves at the adjacent ends of the strips 1 and 3 and 2 and 4. It will thus be seen that when 90 the tongues on the strips 7, 8 and 10 extend into the grooves of the side rails, a frame will be formed which will stretch the canvas cover 5 and hold the same in such a position as to form a table on which the paper 95 hanger may work. Pivoted hooks 7^a are carried by the end bars 7 and 8 adjacent each end thereof and are adapted to engage headed pins 8^a carried by the outer ends of the side rail and the hooks prevent the accidental displacement of the tongues from the grooves 6. In order that the paper hanger may crimp the paper without danger of cutting the canvas cover 5, a pair of strips of metal 11 are secured to the upper sides of 100 the side rails 1 and 3 to overlie the canvas and form a cutting surface and these strips are bent downwardly over the side edges of the strips 1 and 3 to protect the same. The ends of the metal strip are placed so that 110

they adjoin the ends of the strips 1 and 3, thereby avoiding interference with the proper folding of the device. The under sides of the side rails at each end and at 5 their centers are provided with apertures 12 for the reception of the pins carried by the legs to form a connection between said legs and the frame.

Passing now to the description of the 10 legs, each set of legs consist of a pair of bars each designated by the numerals 13 and 14. These bars are placed with their flat sides adjacent and are pivotally connected at their centers as at 15 while the 15 upper and lower ends thereof are beveled as at 16, so that when the device is in assembled position and the legs are spread in the manner illustrated in the drawings the faces 16 at the lower side of the legs 20 will form seats while the beveled ends at the upper sides will form rests on which the under sides of the side and end bars of the top or table are positioned. Centrally of the beveled portions 16 at the upper ends 25 of the legs are suitable upwardly extending dowel pins which are adapted to engage in the apertures at the centers and ends of the side bars to form a connection between the top and the legs. It will thus be seen 30 that when the legs are in place the table or top will be supported a distance above the floor equal to the usual height of an ordinary paper hanger's board.

In order to brace the device against end 35 wise movement a suitable brace structure is provided consisting of the central strip 18, the opposite ends of which are beveled off as shown and provided with apertures 19 for the reception of the pivot pins 20. 40 These pivot pins form connections for the brace bars 21, the adjacent ends of which are provided with the reduced extensions 22 forming shoulders 23 which are adapted to abut the side edges of the center strips 45 10 when the device is in the assembled position. The outer or free ends of the strips of the brace bars are provided with the cut away portion 24 forming substantially triangular extensions, the faces of which are 50 adapted to conform to the inclination of the legs so as to fit snugly against said legs. The shoulders 25 formed by the cut-away portions of the free ends of the brace bars are adapted to engage the inner faces of 55 the legs so as to transmit any motion imparted to said legs directly against the central strip 10 thereby avoiding endwise wabbling of the table. In order to support the pivoted ends of the brace bars in proper po-

sition with relation to the central strip 10, 60 there is provided the clip 26 which is secured to the under side of said strip and is provided with the tongue 27 which engages the under sides of the extensions on the adjacent ends of the brace bars and thus 65 hold said brace bars in operative position.

From the foregoing it will be apparent that a particularly simple construction of table is provided which is particularly adapted for use as a papering board and 70 which may be readily knocked down for transportation. It is to be understood that if so desired a suitable brace bar 28 may be connected between either of the end legs and the center legs at the desire of the user, 75 thereby holding the center leg against wabbling.

While in the foregoing there has been shown and described the preferred embodiment of this invention, it is to be understood that such changes may be made in the combination and arrangement of parts as will fall within the spirit and scope of the appended claims.

What is claimed is:—

1. A paper hanging board comprising a knocked down frame, including side bars, the under sides of the side bars being provided with apertures, legs consisting of a pair of bars pivoted centrally together, 90 dowel pins at the upper ends of the legs adapted to extend into the apertures in the under sides of the side bars of the frame, a flexible cover for said frame, and secured to the side bars, a clip on the central brace 95 of the frame and brace bars removably connected to the clip and engaging the end legs of the table to hold the whole against wabbling.

2. In a paper hanging board comprising 100 a knocked down frame, including a pair of side bars, cross bars removably connected between the side bars and a flexible cover connecting the side bars and forming a top for the device, legs detachably secured to the 105 frame, and metallic angle bars positioned on top of said flexible cover at the longitudinal edges thereof and engaging the cover and the upper side edges of the side bars and extending the whole length of the 110 side bars, as and for the purpose specified.

In testimony whereof I affix my signature in presence of two witnesses.

ISRAEL L. CLARK.
